APPARATUS FOR FEEDING MATERIAL

Warren Dunham Foster, Washington Township,
Bergen County, N. J., assignor to Kinatome
Patents Corporation, a corporation of New
York

Application October 5, 1931, Serial No. 567,109

30 Claims. (Cl. 88—17)

The present invention relates broadly to improved apparatus for feeding material, particularly to apparatus especially adapted for the feeding of film bearing thereupon pictorial or sound images or for exposure to such images, although the utility of the invention is not limited in this respect.

An object of the present invention is to provide simple, inexpensive and effective apparatus whereby a strip of material may be fed from one supporting member to another and an intermediate portion maintained motionless for regularly recurring periods. According to one exemplification of this system of feeding, both the delivery and taking up carriers are driven continuously but at rates of speed which vary in accordance with the intermittency of movement of the intermediate section of the material which is being worked upon, the entire operative length of the material being maintained under a condition of substantially uniform tension. The intermittently operable feeding member disposed between the carriers serves both to draw material directly from the supply carrier and, working through the material, to operate an auxiliary feeding and tensioning device disposed between the feeding member and the supply carrier. The driven taking-up member serves both to move the film away from the intermediate intermittently operating member and to operate an auxiliary feeding and tensioning device disposed therebetween.

Apparatus constructed according to my invention may also be advantageously employed in connection with a continuously operating feeding member for the purpose of compensating for minor irregularities of movement of such member and maintaining the material under an even and uniform flow. This application of my invention is particularly useful in connection with "ripple killing", as this process is often termed in the sound motion picture art.

In the co-pending application of Clarkson Ulysses Bundick and Barton Allen Proctor, Serial Number 44,482, filed July 18, 1925, method and means for feeding material are described and claimed which involve the use of spring pressed members engaging the film. An object of this invention is to provide improved means, by the use of weighted rollers operated solely by gravity and engaging the film adjacent the feeding member for carrying out the Bundick and Proctor method of feeding.

Another object of the present invention is to provide improved auxiliary feeding and tension-

ing means particularly adapted to the handling of relatively heavy masses of material or the successive handling of masses of material of different weight, or the feeding of successive masses of material at different speeds.

Obviously the tension to be applied to the material which is being fed should be initially determined in accordance with the weight of the entire mass of material. Likewise adjustments should be made in accordance with the rate of movement at which the material is fed. When the tension depends upon spring pressure, such adjustment only with difficulty can be explained to the user, particularly if he is an amateur, and is difficult to determine and carry out with accuracy. An object of my invention is to provide means whereby the tension upon the material may be easily and definitely varied by the user before the feeding operation is commenced, preferably by the use of a scale marked in terms of the footage or weight of the material to be fed, or the rate of movement, or both.

An object of the present invention is the provision of improved auxiliary feeding devices and improved tensioning devices for use with material handling apparatus, and also improved arrangement of such devices and the parts thereof.

In the accompanying drawing there is shown, for purposes of illustration only, one preferred embodiment of the present invention, and one preferred modification of such embodiment, it being understood that the drawing does not define the limits of the invention, as changes in the construction and operation disclosed therein may be made without departing from the spirit of the invention or the scope of the broader claims.

In the drawing:

Figure 1 is a side elevational view largely diagrammatic, illustrating one embodiment of the present invention.

Figure 2 is a view taken on the lines 2—2 of Figure 1 looking in the direction of the arrows.

Figure 2—a is a detailed side elevational view of the arrangement of an adjustable weight upon an actuating arm.

Figure 3 is a top plan view of a modification of my invention.

Figure 4 is a side elevational view of the same.

In carrying out the present invention in connection, for example, with the feeding of film, there may be provided an apparatus comprising a main frame F upon which are mounted a delivery spindle 2 and a take-up spindle 3 between which the film f is fed. A delivery carrier 4 is mounted upon the delivery spindle and a take-up

- carrier 5 upon the take-up spindle. Intermediate these carriers are positioned guiding rollers, 7, 8 and 9, each of which rotates upon its fixed axis. For imparting an intermittent or other feeding movement to the film, a toothed feeding sprocket 11 is positioned between the carriers. Between the feeding member 11 and the guiding roller 7 an aperture may be provided, the axis of which is indicated by the dot and dash line 12.

- carrier 4 and draws therefrom a certain amount of film. Upon the next succeeding rotation of the sprocket 11, the portion of the film necessary to compensate for the displacement caused by such rotation is the length of film previously pulled from the carrier 4 and such as at that moment is pulled directly from such carrier. The tension exerted upon the film through the roller 15 serves to cushion such direct movement of film from the carrier. The delivery carrier rotates continuously but its speed of rotation is determined by the effect exerted through the weighted roller 15 in combination with the intermittency of movement of the sprocket 11. The film is maintained under substantially constant tension.
- In addition to the operation above described, the braking shoe 22 and its associated parts, if desired, may be employed. The arm 17, under the influence of the weight thereupon, is normally swung downwardly as shown in Figure 1 so as to bring the shoe 22 in contact with the drum 23 by means of the spring 21, the brake shoe 22 thus tending to prove too free rotation of the delivery spindle 2 and thereby preventing the tension upon the film becoming less than that required for proper feeding. This braking function is particularly useful at the initiation of the feeding operation. In the event of a tendency toward too great tension, however, the tension of the film causes the supporting arm 17 to move upwardly and hence relieve the braking action of the shoe 22. This braking action is also particularly useful in cases of unusual condition of film feeding, such as, for example, binding of a spindle due to improper lubrication, a piece of grit, sudden acceleration or deceleration of the feeding sprocket, or any of the countless irregularities which arise in film feeding. If the movable braking surface 22 is employed, the fixed brake 24 is often unnecessary.
- The operation of the tensioning and feeding roller 25 is analogous to that of the roller 15. As the sprocket 11 revolves, a portion of the film equal to one frame is moved forwardly. The spindle 3 pulls the film away from the sprocket and coils it upon the take-up carrier 5. This movement tends to raise the roller 25 from its lower position as shown in the drawing. Upon the next feeding impulse of the sprocket 11, the action of the roller 25 upon the film is effective for moving the film away from the sprocket. As the sprocket 11 again becomes motionless, the power which is applied to the spindle 3 is effective merely to raise the roller 25 and to coil a portion of a frame upon the carrier 5 and not to jerk the film against the teeth of the sprocket 11. Such jerking would of course be injurious to the perforations of the film. Thus it will be seen that the action of the weighted roller 25 maintains the section of the film between the intermittent feeding member and the taking up carrier constantly in motion and under substantially uniform tension. So far as this portion of the feeding operation is concerned, the spindle 3 may be positively instead of yieldingly driven, and if the range of movement of the weighted roller 25 is sufficiently great, reliance may be placed upon the roller alone to compensate for the difference in speed as the mass of film upon the take up reel is built up. Generally, however, it is preferred to use the conventional frictional drive so that peripheral speed of the carrier 5 will not change rapidly as the mass of film builds up upon it.

The brake shoe 32 may be employed if desired and cooperates with the shoe 33 in a way analogous to that described above.

- It will be noted that the two weighted rollers 5 act in opposition to each other, upon opposite sides of the intermittent feeding member, if the sprocket 11 is of the intermittent type, and of the aperture of the gate, if any, thus also tending to maintain this section of the film motionless and flat where and when such characteristics are needed. Moreover, the pull of one roller upon the film is equalized by that of the other, thus preventing undue pressure between the sides of the teeth of the sprocket 11 and the perforations 15 of the film. Attention is particularly directed to the fact that the entire operative length of film, between the delivery carrier and the take-up carrier, is continuously subjected to the operation of these weighted rollers.
- 20 Figures 3 and 4 illustrate a preferred modification of my invention in which the braking member is completely eliminated.

I mount a roller 41 revoluble upon a shaft 42 in slots 43 formed in each of two parallel members 44 and 45, and engaging the film *f* and bodily supported thereby, as will be readily apparent from the drawing. The members may be formed of fibre. The roller is so positioned relatively to the film carrier and to other supporting or guiding structures that it is disposed within a bight of the film. The parallel members serve to support the roller, and to permit its free rotation as well as its free movement in a direction substantially normal to the line of travel of the film. Such devices may be employed in association with both the delivery and taking-up spindles. As the film is moved by the feeding member 11, the film bodily raises the roller 41, which is disposed between such member and the delivery 35 spindle 2, and the weight thereof is effective during the period of idleness of the feeding member to draw film from the carrier 4 and during the period of operation of the feeding member to cushion the pull thereof upon the mass of film 40 upon the delivery carrier. Similarly, the roller associated with the take-up spindle 3 and supported by the length of film between the feeding member and take-up spindle is effective to draw film away from the feeding member after each 45 operation thereof and to absorb the pulling influence of the take-up spindle during the periods of inactivity of the feeding member. It is of course understood that the operation of this device is such that the entire operative portion of the film is maintained under tension and the two carriers maintained under constant motion.

In the foregoing portion of this specification, it has been stated that the various parts of the invention are so disposed relatively to each other 60 and to the film that both carriers are maintained continuously in motion. If desired, the parts may be so disposed, preferably in combination with braking pressure of relatively great magnitude, that the carriers stop and start in timed relation 65 to the movement of the intermittent member, but such arrangement is not recommended for general purposes.

The upper extremity of the slots within the parallel supporting members, as viewed in Figure 4, is preferably left open so that the user may remove the roller when the film is being threaded—although such removal is not necessary as he can readily pass the film under the roller—or so that he can substitute, as desired, rollers of different weight.

All film engaging rollers are preferably relieved so that they bear only upon the portions of the film which do not bear images thereupon.

As has been previously pointed out, if desired my invention may be applied to a continuously driven sprocket, instead of one which is driven intermittently, for the purpose of making the flow of material fed thereby more smooth and even. Attention is directed to the fact that for such purposes I depend upon the weight of the roller which is bodily supported by the film itself and not upon friction between the film and an idling drum. I depend upon the weight of a member which bodily rides upon the film thus maintaining the film under constant tension and not upon skin friction between the film and a body rotating upon a fixed axis. It has been found that a film may be subjected to relatively great tension during the feeding operation with no injury whatever, provided the tension is continuously maintained. On the other hand, an unsupported loop of slack film, unless of relatively great radius, is in itself destructive of film irrespective of any strain which may be placed upon the perforations.

The advantages of my invention will be evident from the fact that the operation of the conventional intermittent feeding member, in co-operation with the improved auxiliary feeding and tensioning device described herein, serves to feed a film or like material from an idling delivery carrier to a driven take-up carrier, each of such carriers being continuously driven but at rates of speed which vary in step with movement of the intermittent member, the entire operative length 30 of the material being maintained under substantially constant tension. This system of feeding does away with the conventional continuous sprockets with their associated loops of slack film. Under this system, the feeding apparatus is less 40 expensive, wear upon the material is much reduced, breakage rendered very much less frequent, threading and other manipulation made easier, and in the case of motion picture film, greater exactitude of registration at the aperture 45 is secured.

Further advantages arise from the provision of a film engaging member, which is effective for subjecting the film to the desired auxiliary feeding and tensioning influence, which presents a 50 movable surface to the film, thus resulting in less wear or likelihood of damage than is the case when a fixed surface is employed.

Other advantages arise from the fact that this device is very easy of adjustment to conform to 55 different feeding conditions.

In connection with a continuously operated feeding member, this device is simple, inexpensive, and effective, particularly in that it maintains the film under the desired constant flow of 60 movement and under constant tension.

I claim:

1. In a film handling apparatus, an idling delivery carrier, a continuously driven take-up carrier, an intermittently driven toothed feeding member positioned between said carriers for drawing perforated film from said delivery carrier and feeding it toward said take-up carrier, a roller characterized by substantial weight bodily supported upon the film between said delivery 70 carrier and said intermittent feeding member and angularly movable with the film whereby each feeding impulse of said intermittent member raises said roller thereby cushioning the pull of said feeding member and during each period of 75

inactivity of said intermittent member said roller upon its downward gravitational movement is effective to draw film from said delivery carrier, thereby maintaining said delivery carrier under 5 continuous movement and maintaining the film under continuous tension between said intermittent feeding member and said delivery carrier; and a roller characterized by substantial weight bodily supported upon the film between said take-up carrier and said intermittent feeding member and angularly movable with the film, whereby during each period of inactivity of said intermittent feeding member said continuously operated take-up carrier raises said roller thereby cushioning the perforations of the film against strain 10 from the teeth of said intermittent feeding member and during the period of operation of said intermittent feeding member the gravitational downward movement of said roller is effective to move the film fed by said intermittent member away therefrom and toward said take-up carrier, thereby maintaining the section of the film between said intermittent feeding member and said take-up carrier under continuous motion and 15 tension.

2. In a film handling apparatus, an idling carrier, an intermittently driven toothed feeding member for drawing perforated film directly from said idling carrier, a roller characterized by substantial weight and means for mounting said roller so that it is bodily supported upon the film between said delivery carrier and said intermittent feeding member and angularly movable with the film, the weight of said roller and the position of said mounting means relative to said idling carrier and said feeding member being so arranged that each feeding impulse of said intermittent feeding member raises said roller thereby cushioning the pull of said feeding member and during each period of inactivity of said intermittent feeding member said roller upon its downward gravitational movement is effective to draw film from said idling carrier thereby maintaining said idling carrier under continuous movement and maintaining the film under continuous tension between said intermittent feeding member and said delivery carrier.

3. In a film handling apparatus, a continuously driven taking up carrier, an intermittently driven toothed feeding member for advancing film toward said driven carrier, said continuous carrier being so disposed in relation to said feeding member that it draws film directly therefrom, a roller characterized by substantial weight, and means for mounting said roller so that it is bodily supported upon the film between said take-up carrier and said intermittent feeding member and angularly movable with the film, the weight of said roller and the position of said mounting means relative to said idling carrier and said feeding means being so arranged that during each period of inactivity of said intermittent feeding member the force of said continuously operated take-up carrier is employed for raising said roller thereby cushioning the perforations of the film against strain from the teeth of said intermittent feeding member and during the period of operation of said intermittent feeding member the gravitational downward movement of said roller is effective to move the film fed by said intermittent member away therefrom and toward said take-up carrier thereby preventing the creation of slack, thereby maintaining the section of the film between said intermittent feeding member and said take-up carrier under continuous motion and tension.

4. In a film handling apparatus, an idling delivery carrier, a continuously driven take-up carrier, an intermittently driven toothed member positioned between said carriers for drawing perforated film from said delivery carrier and feeding it toward said take-up carrier, a roller bodily supported upon the film between said delivery carrier and said intermittent feeding member and angularly movable with the film, a supporting member movably mounted upon said apparatus, said roller being mounted upon said supporting member for rotation in respect thereto and for bodily movement therewith, whereby each feeding impulse of said intermittent member raises said roller and said supporting member thereby cushioning the pull of said feeding member and during each period of inactivity of said intermittent member said roller upon its downward gravitational movement is effective to pull film from said delivery carrier, thereby maintaining said delivery carrier under continuous movement and maintaining the film under continuous tension between said intermittent feeding member and said delivery carrier; and a roller bodily supported upon the film between said take-up carrier and said intermittent feeding member and angularly movable with the film, a supporting member movably mounted upon said apparatus, said roller being mounted upon said supporting member for rotation in respect thereto and for bodily movement therewith, whereby during each period of inactivity of said intermittent feeding member said continuously operated take-up carrier raises said roller and said supporting member thereby cushioning the perforations of the film against strain from the teeth of said intermittent feeding member and during each period of operation of said intermittent feeding member the gravitational downward movement of said roller is effective to move the film fed by said intermittent member away therefrom and toward said take-up carrier, thereby maintaining the section of film between said intermittent feeding member and said take-up carrier under continuous motion and tension.

5. In a film handling apparatus, an idling delivery carrier, a continuously driven take-up carrier, an intermittently driven toothed member positioned between said carriers for drawing perforated film from said delivery carrier and feeding it toward said take-up carrier, a roller bodily supported upon the film between said delivery carrier and said intermittent feeding member and angularly movable with the film, a supporting arm pivotally mounted upon said apparatus, said roller being mounted upon said arm at a point thereon relatively remote from such mounting, and a weight disposed upon said arm, whereby each feeding impulse of said intermittent member raises said weighted roller thereby cushioning the pull of said feeding member and during each period of inactivity of said intermittent member said weighted roller upon its downward gravitational movement is effective to pull film from said delivery carrier, thereby maintaining said delivery carrier under continuous movement and maintaining the film under continuous tension between said intermittent feeding member and said delivery carrier; and a roller bodily supported upon the film between said take-up carrier and said intermittent feeding member and angularly movable with the film, a supporting arm pivotally mounted upon said apparatus, said roller being mounted upon said arm at a point relatively remote from such

- mounting, and a weight disposed above said arm, whereby during such period of inactivity of said intermittent feeding member said continuously operated take-up carrier raises said weighted 5 roller thereby cushioning the perforations of the film against strain from the teeth of said intermittent feeding member and during the period of operation of said intermittent feeding member the gravitational downward movement 10 of said weighted roller is effective to move the film fed by said intermittent member from said intermittent member toward said take-up carrier, thereby maintaining the section of film between said intermittent feeding member and said take-up carrier under continuous motion and tension.
6. In a film handling apparatus, an idling delivery carrier, an intermittently driven toothed member for drawing perforated film directly 20 from said delivery carrier, a roller, a supporting arm for said roller, a pivotal mounting upon said apparatus for said arm so disposed that said roller is bodily supported upon the film between said delivery carrier and said intermittent 25 feeding member and angularly movable with the film, said roller being mounted upon said arm at a point thereon relatively remote from such mounting, and a weight disposed upon said arm, said mounting and the weight applied to said 30 roller being so arranged in relation to said continuous carrier and said intermittent member that each feeding impulse of said intermittent member raises said weighted roller thereby absorbing a large portion of the force of said 35 impulse and cushioning the pull of said feeding member against the mass of the film and during each period of inactivity of said intermittent member said weighted roller upon its downward gravitational movement is effective to pull film directly from said delivery carrier, thereby preventing the accumulation of slack and maintaining said delivery carrier under continuous movement and maintaining the film under continuous 40 tension between said intermittent feeding member and said delivery carrier.
7. In a film handling apparatus, a continuously driven take-up carrier, an intermittently driven toothed member for advancing perforated film toward said take-up carrier, said continuous 45 carrier and said intermittent member being so disposed that said carrier draws film directly and continuously from said toothed intermittent member, a roller, a supporting arm, a pivotal mounting upon said apparatus for said arm so 50 disposed that said roller is bodily supported upon the film between said take-up carrier and said intermittent feeding member and angularly movable with the film, said roller being mounted upon said arm at a point relatively remote from such 55 mounting, and a weight disposed upon said arm, said mounting and the weight of said roller being so disposed that during each period of inactivity of said intermittent feeding member the force of said continuously operated take-up 60 carrier is employed to raise said weighted roller thereby absorbing a large portion of said force and cushioning the perforations of the film against strain from the teeth of said intermittent feeding member and during the period of operation 65 of said intermittent feeding member the gravitational downward movement of said weighted roller is effective to move the film fed by said intermittent member from said intermittent member toward said take-up carrier thereby preventing the accumulation of slack, 70 thereby maintaining the section of film between said intermittent feeding member and said take-up carrier under continuous motion and tension.
8. In a film handling apparatus, an idling delivery carrier, a continuously driven take-up carrier, an intermittently driven toothed member positioned between said carriers for drawing perforated film from said delivery carrier and feeding it toward said take-up carrier, a roller bodily 75 supported upon the film between said delivery carrier and said intermittent feeding member and angularly movable with the film, a supporting arm pivotally mounted upon said apparatus, said roller being mounted upon said arm at a point thereon relatively remote from such mounting, and a weight disposed upon said arm, whereby each feeding impulse of said intermittent member raises said weighted roller upon its downward gravitational movement is effective to pull film from said delivery carrier, thereby maintaining said delivery carrier under continuous movement and maintaining the film under continuous tension.
9. In a film handling apparatus, an idling delivery carrier, a continuously driven take-up carrier, an intermittently driven toothed member positioned between said carriers for drawing perforated film from said delivery carrier and feeding it toward said take-up carrier, a roller bodily supported upon the film between said delivery carrier and said intermittent feeding member and angularly movable with the film, a supporting arm pivotally mounted upon said apparatus, said roller being mounted upon said arm at a point thereon relatively remote from such mounting, a weight disposed upon said arm, whereby each feeding impulse of said intermittent member raises said weighted roller thereby cushioning the pull of said feeding member and during each period of inactivity of said intermittent member said weighted roller upon its downward gravitational movement is effective to pull film from said delivery carrier, thereby maintaining said delivery carrier under continuous movement and maintaining the film under continuous tension.

mittent member said roller upon its downward gravitational movement draws film from said delivery carrier, thereby maintaining said delivery carrier under continuous movement and maintaining the film under continuous tension between said intermittent feeding member and said delivery carrier.

14. In a film handling apparatus, a continuously driven take-up carrier, an intermittently driven toothed feeding member for moving film toward said take-up carrier, a roller characterized by substantial weight bodily supported upon the film between said take-up carrier and said intermittent feeding member and angularly movable with the film, and means for maintaining said roller against substantial longitudinal movement in respect to the film, said roller being so disposed in relation to said carrier and said intermittent feeding member that during each period of inactivity of said intermittent feeding member said continuously operated take-up carrier raises said roller thereby cushioning the film against strain and during the period of operation of said intermittent feeding member the gravitational downward movement of said roller is effective to move the film fed by said intermittent member away therefrom and toward said take-up carrier, thereby maintaining the section of film between said intermittent feeding member and said take-up carrier under continuous motion and tension.

15. In a film handling apparatus, a film-support, a toothed member for feeding a film positioned upon said support in relation thereto, a roller bodily supported upon the film between said support and said feeding member and angularly movable therewith under the influence thereof during such feeding operation, the disposition of said roller in relation to said film support and said toothed member being such that said roller conditions the movement of the entire stretch of the film between said film support and said toothed feeding member, and guiding means limiting the movement of said roller in a direction along the path of the film between said film-support and said toothed member while allowing free movement thereof in a direction substantially normal to such path.

16. In a film handling apparatus, a film carrier, a toothed member for feeding a film positioned upon said carrier in relation thereto, and a roller of material weight entirely supported by said film and freely movable in response to its operation disposed between said film carrier and said toothed member for assisting in the film feeding operation, said roller being so disposed in relation to said toothed member and said carrier that it conditions the operation of the entire stretch of the film therebetween.

17. In a film handling apparatus, a film-support, a toothed member for feeding a film positioned upon said support, a roller resting upon the film between said support and said feeding member and bodily supported by the film for assisting in the film-feeding operation, the disposition of said roller in relation to said film support and said toothed member being such that said roller conditions the movement of the entire stretch of the film between said film support and said toothed member, and means for selectively changing the force to which the film is subjected by means of said roller.

18. In a film handling apparatus, a film-support, a toothed member for feeding a film positioned upon said support, a roller resting upon

the film between said support and said feeding member and bodily supported by the film for assisting in the film-feeding operation, the disposition of said roller in relation to said film support and said toothed member being such that said roller conditions the movement of the entire stretch of the film between said film support and said toothed member, an arm pivoted upon said apparatus said roller being rotatably mounted thereupon at a point relatively remote from such mounting, and a weight disposed upon said arm and movable thereupon between said mounting and the point of attachment of said roller to said arm, for the purpose of changing the force to which the film is subjected by means of said roller.

19. In a film handling apparatus, a film-support, a member for feeding a film positioned upon said support, a roller resting upon the film between said support and said feeding member and bodily supported by the film for assisting in the film-feeding operation, an arm pivoted upon said apparatus, said roller being rotatably mounted thereupon at a point relatively remote from the mounting thereof, a weight disposed upon said arm and movable thereupon between said mounting and the point of attachment of said roller to said arm, for the purpose of changing the weight to which the film is subjected by means of said roller, and indicia placed upon said arm indicating the point to which said weight should be moved to secure desired conditions of film feeding under the conditions stated by said indicia.

20. In a film handling apparatus, a film-support, a member for feeding a film positioned upon said support, and means for selectively subjecting the section of film between said support and said member to varying degrees of tension, said means comprising a member engaging the film between said film support and said feeding member, means for applying force to said member whereby such section of the film is subjected to tension, the disposition of said film engaging member in relation to said film-support and said feeding member being such that the force applied to the film through said member conditions the entire stretch of the film between said film support and said feeding member, a control member movable at will for changing the degree of force so applied, and indicia placed upon said apparatus coacting with said control member indicating the point to which said control member should be moved to secure desired conditions of film feeding under the conditions stated by said indicia.

21. In a film handling apparatus, a film-support, a member for feeding a film positioned upon said support, and means for selectively subjecting the section of film between said support and said member to varying degrees of tension, said means comprising a member engaging the film between said film support and said feeding member, means for applying force to said member whereby such section of the film is subjected to tension, the disposition of said film engaging member in relation to said film-support and said feeding member being such that the force applied to the film through said member conditions the entire stretch of the film between said film-support and said feeding member, a control member movable at will for changing the degree of force so applied, and indicia placed upon said means for applying force of said member and coacting with said control member to indicate the point to which said control member should be moved to secure desired conditions of film feed-

- ing under the conditions stated by said indicia.
22. In a film handling apparatus, a spindle adapted for the removable mounting of a film carrier thereupon, a toothed member for feeding a film in relation to a carrier mounted thereupon, and means for controlling the tension of that portion of the film extending between said feeding member and said carrier, said means comprising a roller bodily supported upon the film between said feeding member and said carrier, a supporting arm, said roller being mounted upon said arm, a brake drum revoluble with said spindle, a brake shoe for cooperation with said brake drum, and a leaf spring one end of which is attached to said arm and upon the other end of which said brake shoe is mounted whereby the movement of said arm applies said brake shoe to said drum.
23. In a film handling apparatus, a spindle adapted for the removable mounting of a film carrier thereupon, a toothed member for feeding a film in relation to a carrier mounted thereupon, and means for controlling the tension of that portion of the film between said feeding member and said carrier, said means comprising a roller bodily supported upon the film between said feeding member and said carrier, a pivotally mounted arm, said roller being mounted upon said arm at a point remote from the mounting thereof, said roller being subjected to substantial weight in order to maintain the film under tension, a brake shoe drum revoluble with said spindle, a brake shoe for cooperation with said drum, and a supporting member for said shoe attached to said pivoted arm adjacent said pivot whereby the movement of said arm immediately applies said shoe to said brake drum.
24. In a film handling apparatus, two supporting members, a power driven toothed feeding member engaging the film between said supporting members for feeding the film from one toward the other, a first roller rotatably mounted upon a fixed axis and engaging the film fed by said feeding member upon one side of said toothed member, a second roller rotatably mounted upon a fixed axis and engaging the film upon the opposite side of said feeding member, a first roller of substantial weight engaging the film between said first axially fixed roller and its relatively adjacent supporting member and bodily supported upon the film and so disposed in relation thereto as to be rotatable in respect thereto and angularly movable therewith under the influence thereof and a second roller of substantial weight engaging the film between said second axially fixed roller and its relatively adjacent supporting member and bodily supported upon the film and so disposed in relation thereto as to be rotatable in respect thereto and angularly movable therewith under the influence thereof, said two axially fixed rollers being so placed relatively to said toothed feeding member that said toothed feeding member is positioned within a bight in the film and said two angularly and rotatably movable rollers being so positioned relatively to each other that the film forming such bight is subjected to opposing influence therefrom whereby the film fed by said toothed feeding member is protected from irregularities of movement.
25. In a film handling apparatus, a support, a toothed feeding member and a film-supporting member between which a film extends, said members being mounted upon said support, two spaced film-engaging rollers positioned between said film supporting member and said film-feeding member,

said rollers being mounted upon said support for axial movement only relatively thereto, and a tensioning roller placed upon the film between said axially fixed rollers and being bodily supported by the film forming a bight therebetween, said bight during a film feeding operation increasing and diminishing and tending to equalize the tension of the entire stretch of film between said film supporting member and said toothed feeding member thereby assisting in the feeding operation, said roller being so disposed in relation to said members that said roller influences the entire stretch of film between said members.

26. In a film handling apparatus, a toothed film feeding member, a film supporting member positioned upon each side of said film feeding member, and a film tensioning roller of substantial weight placed upon and supported by the film between each of said film supporting members and said film feeding member, said two film tensioning rollers being so disposed that the weight of each thereof is opposed to that of the other and thereby subjects the film to a substantially equal tension from opposite directions in relation to said film feeding member.

27. In a film handling apparatus, a film supporting member, a toothed member for feeding a film in relation thereto, and film tensioning means cooperating with said members, said tensioning means comprising guiding means for the film mounted independently of said feeding member and of said supporting member whereby a portion of the section thereof between said feeding member and said supporting member may be disposed within a bight, and a roller of substantial weight bodily supported upon the film and angularly movable therewith under the influence thereof and cooperating with said guiding means to form such bight, whereby such section of the film between said feeding member and supporting member is subjected to tension.

28. In a film handling apparatus, a film supporting member, a toothed member for feeding a film in relation thereto, and means for controlling the tension of that portion of the film between said feeding member and said supporting member, said means comprising guiding means for the film mounted independently of said feeding member whereby a portion of the section thereof between said feeding member and said supporting member may be disposed within a bight, a roller bodily supported upon the film and cooperating with said guiding means to form such bight, whereby such section of the film between said feeding and supporting members is subjected to tension, a pivoted arm upon which said roller is mounted, and a weight upon said arm.

29. In a film handling apparatus, a film carrier, a toothed member for feeding a film positioned upon said carrier, a weighted tensioning member bodily supported upon the film between said carrier and said feeding member, said weighted tensioning member being so disposed in relation to said carrier and said toothed feeding member that it conditions the operation of the entire stretch of film between said carrier and said toothed member, and a guiding structure in which said tensioning member is movable in a direction angular to the line of travel of the film adjacent said roller whereby the film is subjected to tension in substantially fixed longitudinal relation to such line of travel.

30. In a film handling apparatus, a carrier, a toothed member for feeding a film positioned upon said carrier in relation thereto, a weighted

tensioning roller bodily supported upon the film between said carrier and said feeding member, said weighted roller being so disposed in relation to said carrier and said toothed member that it conditions the operation of the entire stretch of the film between said carrier and said feeding member, an axial formation extending from said roller in both directions, and a guiding structure for said roller characterized by parallel slots,

disposed in angular relation to the line of travel of the film adjacent said roller, in which said formation is angularly movable, whereby during the feeding operation upon the film said roller is revoluble in respect to the film and angularly and freely movable therewith and maintained against substantial movement along such line of travel. 5
